UNITED STATES PATENT OFFICE.

JOE SVEDA, OF CORBIN, BRITISH COLUMBIA, CANADA.

DESIGN FOR A CHRISTMAS TREE.

44,878.

Specification for Design.

Patented Nov. 11, 1913.

Application filed January 16, 1913. Serial No. 742,486. Term of patent 3½ years.

To all whom it may concern:

Be it known that I, JOE SVEDA, a subject of the King of Hungary, residing at Corbin, British Columbia, Canada, have invented a certain new, original, and ornamental Design for Christmas Trees, of which the following is the specification, reference being had to the accompanying drawing, forming a part thereof, and in which—

Figure 1 is a front elevation and Fig. 2 a

top plan of a Christmas tree, illustrating my new design.

I claim:—

The ornamental design for a Christmas tree, as shown.

JOE SVEDA.
